UNITED STATES PATENT OFFICE.

J. C. SIMONDS AND FREEMAN GODFREY, OF GRAND RAPIDS, MICHIGAN.

IMPROVEMENT IN WATER-WHEELS.

Specification forming part of Letters Patent No. 44,227, dated September 13, 1864.

To all whom it may concern:

Be it known that we, J. C. SIMONDS and FREEMAN GODFREY, both of Grand Rapids, in the county of Kent and State of Michigan, have invented a new and Improved Water-Wheel; and we do hereby declare that the following is a full, clear, and exact description of the same, reference being had to the accompanying drawings, making a part of this specification, in which—

Figure 1 is a side view of our invention; Fig. 2, a plan or top view of the same; Fig. 3, a vertical section of the same taken in the line $x x$, Fig. 2.

Similar letters of reference indicate corresponding parts in the several figures.

This invention relates to a new and improved horizontal water-wheel of that class in which the water passes underneath the wheel and out through the top of the same.

To enable those skilled in the art to fully understand and construct our invention, we will proceed to describe it.

The wheel is composed of a central hub, a , of cylindrical form, through which the shaft A passes, and an outer rim, b , between which and the hub a are the buckets c . These buckets are of a spiral form, their lower edges having a radial position, and as they extend upward and backward the spiral curve is gradually flattened, as shown at d in Fig. 3, and they are gradually inclined downward from their inner to their outer edges, so that their upper edges will be inclined about ten degrees from a horizontal line. The upper edges of the buckets have nearly a tangential position with the hub a , so that the outer end of the upper edge of one bucket will be nearly in a radial line with the inner edge of the adjoining bucket, as shown in Fig. 2, and the spaces between the buckets gradually contract from their lower to their upper ends and the issues—that is to say, the upper ends of the spaces between the buckets, owing to the winding spiral form of the latter,

are deeper or wider at their outer than at their inner ends. By this form and arrangement of the buckets, the wheel offers the least possible resistance to the tail or back water and the water is allowed to escape from the issues freely or in a direction which the centrifugal force of the wheel would naturally impel it; hence the water is not allowed to act as a drag upon the wheel, and the water acts or impinges upon the buckets at right angles. In the under side of the hub a of the wheel there is made a circular recess, e , which forms a flange, f , all around the lower edge of the hub, and this flange fits and works in a recess or rabbet, g , at the upper edge of the block h , on which the shaft A is stepped. (See Fig. 3.) The water passes into a scroll, C , underneath the wheel. The lower edge of the rim b of the wheel is provided with a horizontal flange, i , which works within a rim, j , on the bed D , in which the scroll C is formed or made. This scroll C is circular in its horizontal section, its bottom k being of a scroll or spiral form, as shown chiefly by dotted lines in Figs. 1 and 3. This scroll or spiral water-passage gives a proper upward direction to the water, while the flange f forms a smooth, unbroken surface at the inner side of the scroll or water-passage around the step of shaft A .

Having thus described our invention, what we claim as new, and desire to secure by Letters Patent, is—

The circular recess e in the bottom of the hub a of the wheel forming the flange f , to fit and work in the recess or rabbet g in the block h in its arrangement with the scroll or spiral water-passage C , substantially as and for the purpose specified.

J. C. SIMONDS.
FREEMAN GODFREY.
